(57) **CLAIM**

We claim the ornamental design for a body for vacuum cleaner, as shown and described.

DESCRIPTION

FIG. 1 is a top, front, and left side perspective view of a body for vacuum cleaner showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, front, and left side perspective view of the body for vacuum cleaner of FIG. 1 shown in use with a hose and a brush; and,

FIG. 9 is a top, front, and left side perspective view of the body for vacuum cleaner of FIG. 1 shown in use as a robot vacuum cleaner.

The broken lines in FIGS. 8 and 9 are for illustrative purposes only and form no part of the claimed design.
